UNITED STATES PATENT OFFICE

144,213

DESIGN FOR A TAPE DISPENSER

Harry Preble, Jr., New York, N. Y., assignor to International Plastic Corporation, Morristown,
N. J., a corporation of Illinois

Application October 6, 1945, Serial No. 122,606

Term of patent 14 years

(Cl. D74—1)

To all whom it may concern:

Be it known that I, Harry Preble, Jr., a citizen of the United States, residing at New York, in the county of New York and State of New York, have invented a new, original, and ornamental Design for a Tape Dispenser, of which the following is a specification, reference being had to the accompanying drawing, forming a part thereof.

In the drawing:

Figure 1 is a front perspective view of a tape
dispenser embodying my design;
Figure 2 is a left side view;
Figure 3 is a right side view; and
Figure 4 is a plan view.
I claim:
The ornamental design for a tape dispenser, substantially as shown.

HARRY PREBLE, JR.
